UNITED STATES PATENT OFFICE

157,214

NEGLIGEE

Murray Taradash, Fall River, Mass.

Application July 23, 1948, Serial No. 147,732

Term of patent 7 years

(Cl. D3—26)

To all whom it may concern:

Be it known that I, Murray Taradash, a citizen of the United States, residing at Fall River, in the county of Bristol, and State of Massachusetts, have invented a new, original, and ornamental Design for a Negligee, of which the following is a specification, reference being had to the accompanying drawing, constituting a part thereof:

Fig. 1 is a front view of a negligee, embodying the novel design; and

Fig. 2 is a rear view thereof.

I claim:

The ornamental design for a negligee, substantially as shown.

MURRAY TARADASH.
